(57) **CLAIM**

The ornamental design for a loudspeaker housing, as shown and described.

DESCRIPTION

FIG. 1 is a perspective view of a loudspeaker housing showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view, the opposite side elevational view being a mirror image thereof;

FIG. 7 is a perspective view of a second embodiment of FIG. 1;

FIG. 8 is a front elevational view thereof;

FIG. 9 is a rear elevational view thereof;

FIG. 10 is a side elevational view, the opposite side elevational view being a mirror image thereof;

FIG. 11 is a top plan view thereof;

FIG. 12 is a bottom plan view thereof;

FIG. 13 is a perspective view of a third embodiment of FIG. 1;

FIG. 14 is a front elevational view thereof;

FIG. 15 is a rear elevational view thereof;

FIG. 16 is a side elevational view, the opposite side elevational view being a mirror image thereof;

FIG. 17 is a top plan view thereof; and,

FIG. 18 is a bottom plan view thereof.

The broken line showings of the rectangles on the front faces, the handle grips, the rectangles on the rear faces, the parallel lines on the top surface and the circular feet on the bottom surface are for illustrative purposes only and form no part of the claimed design.
